UNITED STATES PATENT OFFICE

JOHN E. WALSH, OF CHICAGO, ILLINOIS, ASSIGNOR TO SELF LOCKING SCHURMANN COMPANY, A CORPORATION OF ILLINOIS

CUSHIONED EGG CARTON

Application filed July 11, 1927. Serial No. 204,709.

The ordinary egg carton, made of light cardboard, does not afford much protection to the eggs therein if the filled carton is set down heavily or struck on the bottom or the 5 sides with sufficient force to break an egg in the event that the blow came directly upon the egg.

The object of the present invention is to provide a simple and novel expedient that 10 will not add greatly to the cost of a carton, by means of which eggs packaged in the carton will be effectively cushioned.

The various features of novelty whereby my invention is characterized will herein- 15 after be pointed out with particularity in the claims; but, for a full understanding of my invention and of its objects and advantages, reference may be had to the following detailed description taken in connection with 20 the accompanying drawings, wherein:

Figure 1 is a top plan view, with a fragment of the cover broken away, of a carton arranged in accordance with my invention; Fig. 2 is a section on a larger scale taken 25 on line 2—2 of Fig. 1, showing the carton closed and eggs therein, and illustrating in dotted lines the position of the cover and of the cushions when the carton is opened and before the eggs are inserted; Fig. 3 is 30 a top plan view of one end of the open carton, on the same scale as Fig. 2, showing the condition of the cushions before the eggs are inserted; Fig. 4 is a plan view of the blank for forming the longitudinal partition and the cushions; and Fig. 5 is a per- 35 spective view, on a larger scale, of one end of the blank folded and ready to be inserted in the carton.

Referring to the drawings, 1 represents 40 the rectangular body and 2 the cover of a well known form of egg carton, namely a carton which, with the exception of the longitudinal partition, is made from a single blank. The front wall 3 of the carton is 45 lower than the rear wall to which the cover is attached, and has connected thereto a false top whose width is equal to that of the carton and which is provided along its free long edge with an attaching strip 4 to be secured 50 to the rear wall of the carton. The trans-

verse partitions 5 are made by slitting the false top to produce a series of leaves joined to the attaching strip and to the front wall of the carton by triangular corner pieces 6. When the leaves are swung down at right angles to the bottom of the carton, only the 55 triangular corner pieces remain in a horizontal plane. It is customary to provide a central longitudinal partition interlocked with the transverse partitions formed by the 60 leaves, for the purpose of dividing the interior of the carton into two rows of compartments. In accordance with the present invention I so construct this longitudinal partition that it provides effective cushions 65 for the eggs.

The longitudinal partition, with the cushioning means, may conveniently be in the form of a single blank of cardboard or the like comprising two central panels 7 and 8, 70 each having approximately the shape of the ordinary single partition, these panels or sections being symmetrically disposed with respect to a longitudinal center line, together with cushioning wings. As is usual in these 75 longitudinal partition members, slots 9 are cut inwardly through those edges of the sections 7 and 8 that are the lower edges of the partition when the latter is set into the carton. These slots may be said to divide the 80 lower marginal portion of each section into feet. The wings are in the form of extensions 10 to the feet; each wing being of such a width as to fit readily between two adjacent trans- 85 verse partitions in the carton.

The blank may be scored along a central longitudinal line 11 and along lines 12, 12 that mark the lower edges of the partition panels proper. In using the combined partition and cushion, it is folded along the 90 central longitudinal line and the wings are then folded so as to extend outwardly in opposite directions from the double walled partition as shown in Fig. 5. If desired, the panels 7 and 8 may be glued or otherwise 95 secured together when lying against each other.

When a carton is to be filled, it is opened up in the usual way from a collapsed condition and the transverse leaves or partitions 100

are swung down so as to stand at right angles to the bottom. The longitudinal partition, in the condition shown in Fig. 5, is then pressed down and interlocked with the transverse partitions in the usual way, permitting the cushioning wings to extend diagonally upwardly and outwardly above the top of the carton as shown in Fig. 3 and in dotted lines in Fig. 2. The eggs, such as indicated at A, are placed in the carton, bending the cushioning wings more or less. When the cover of the carton is swung down it depresses the eggs, still further bending the cushioning wings and causing them to snap down underneath the triangular corner pieces 6 on the transverse partitions of the carton. Thereafter, even though an egg be lifted from its compartment, the underlying cushioning wing cannot spring up so as to project above the false top of the carton, because the triangular corner piece that overlies the free end of the wing acts as a stop to limit the upward movement of the free end of the wing.

The parts are so proportioned that the eggs to be packed are shorter than the height of the carton, so that the eggs are supported at some distance above the bottom of the carton, somewhat in the manner that a prospective diver is supported when he stands on the outer end of a spring board. Furthermore, the wings, in tending to straighten out, press the eggs inwardly toward the central longitudinal position, thus holding the eggs away from the sides of the carton.

It will therefore be seen that if a carton be set down heavily, there is no danger of breaking the eggs because they rest upon spring-like supports. Furthermore, a light blow that would otherwise still be sufficient to crack an egg, against the side of the carton, is absorbed by the inward yielding of the side wall, either wholly or in part, before being transmitted to the egg lying inwardly from the point at which the blow is struck; and therefore the egg is protected against breakage.

It will further be seen that my improved construction gives added strength to the carton, not only because of the stiff backbone that the double longitudinal partition may be said to constitute, but also because the wings may fit between the transverse partitions and thus form braces for the latter.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. In combination, a container, a vertical partition therein, and a resilient article-sup-

porting element extending from the lower end of said partition upwardly and outwardly to and slidably engaged with a side wall of the container.

2. In combination, a container, a vertical partition of resilient material therein, said partition having an extension directed upwardly and outwardly from its lower end to and in sliding engagement with a side wall of the container. 70

3. In combination, an egg carton having a vertical longitudinal partition and a vertical transverse partition, and wings on the longitudinal partition extending from the lower end outwardly and upwardly to and slidably engaged with the sides of the carton. 75

4. In combination, an egg carton having a vertical longitudinal partition and a vertical transverse partition, and wings on the longitudinal partition extending from the lower end outwardly and upwardly to the sides of the carton, said wings being of a width to fit between and brace the transverse partitions and fitting slidably at its upper ends against the sides of the carton. 80

5. In combination, a carton, a vertical partition in the carton, said partition consisting of a sheet folded in the middle and along two lines on opposite sides of the middle, the two central sections forming the partition proper of double thickness and the two side sections extending upwardly and outwardly to the sides of the carton in the vicinity of the top of the carton. 85

6. In combination, a carton having vertical transverse partitions, and a longitudinal partition interlocked with the transverse partitions, said longitudinal partition comprising a sheet folded upon itself and having wings extending from the lower end of the partition upwardly and outwardly to and slidably engaged with the side walls of the carton between said transverse partitions. 90

7. In combination, an egg carton having partitions dividing it into compartments, and yieldable false bottoms for said compartments extending downwardly and inwardly from elevated points on the sides of the carton, the upper ends of said false bottoms being loosely engaged with the said sides and being capable of sliding down along the latter under the weight of eggs resting thereon. 100

8. In combination, a container, a vertical partition therein, and a resilient article-supporting element extending from the lower end of said partition upwardly and outwardly to and terminating at a side wall of the container, the upper outer end of said element being loosely engaged with said side wall so as to permit it to slide down along the latter 105 when a load is placed upon said element.

In testimony whereof, I sign this specification.

JOHN E. WALSH.
